INVENTOR

Edward A. Rein

UNITED STATES PATENT OFFICE.

EDWARD A. REIN, OF PHILADELPHIA, PENNSYLVANIA.

GAS-REGULATOR FOR GAS-ENGINES.

1,199,421.

Specification of Letters Patent. Patented Sept. 26, 1916.

Application filed September 21, 1915. Serial No. 51,813.

To all whom it may concern:

Be it known that I, EDWARD A. REIN, a citizen of the United States, and resident of Philadelphia, Pennsylvania, have invented 5 certain new and useful Improvements in Gas-Regulators for Gas-Engines, of which the following is a specification.

Rubber bags are commonly interposed between city gas mains and the intake valves 10 of gas engines to reduce fluctuations in pressure of gas delivered to the engine from the main. Such rubber bags deteriorate rapidly and are easily subject to leakage and have other faults known to users of them. 15 Other appliances used for a similar purpose are quite complicated or give off the odor of gas, are subject to freezing, or have other disadvantages.

The present invention remedies the above 20 difficulties. It consists, broadly stated, in a metal gas container or reservoir having thin, flexible side walls with or without a spring to augment the compressive capacity of the walls, a supply opening for gas from 25 the main, a discharge opening for connection to the engine and a spring-actuated check- or reducing-valve intermediate the container and the discharge opening.

The accompanying drawing shows one 30 exemplifying embodiment of the invention, the best that I have up to the present time devised; but it is to be understood that the invention is capable of embodiment in other forms.

35 Figure 1 is a side elevation. Fig. 2 is a vertical section. Fig. 3 is a vertical section in a plane perpendicular to Fig. 2. Fig. 4 is a horizontal section.

The container in an approved embodiment 40 consists of an edge wall 1 of relatively heavy sheet metal and flexible side walls 2 of relatively thin sheet metal—usually metal of high flexibility and strength, such as steel. The side walls are united to the edge wall in 45 any suitable way by seaming, soldering or the like. Such structural details are not a part of this invention.

50 Preferably, although not necessarily in all cases, the side walls are connected substantially at the center by a contractile spring 3. This is satisfactory when made of phosphor-bronze. I have devised means for putting the spring in position which avoids difficulties that would otherwise be 55 encountered. The ends of the spring, which are in the form of a helix, are connected to

the stems 4 of buttons 5, the heads whereof lie outside of and are soldered to the walls 2.

The walls are apertured as at 6 to accommodate the stems of the buttons. In assembling, one end of the spring is connected to the stem of one of the buttons and the other end of the spring is then inserted in one of the holes 6 and the spring is screwed in through the hole until the button and its 65 stem are in proper position as shown in Fig. 3. The other end of the spring is then pulled out through the opposite hole and attached to the stem of the other button; the spring is then allowed to pull the button into 70 position and that button is secured. Evidently the holes in the side plates 2 need not be as large as the outside diameter of the spring, but only a little larger than the diameter of the wire of which the spring is 75 composed.

At a suitable place, usually one of the ends of the container, is a fitting F, which conveniently comprises passages for the entrance and exit of gas, and the valve, so that 80 the fitting may be assembled separately from the container and inserted and secured thereto as a unit.

The fitting has a body 7 provided with a connection 8 for a gas pipe to supply city 85 gas. The gas enters the container through aperture 9 in edge wall 1. Centrally located in the fitting is tube 10, secured to the fitting at 11. The inner end of this tube is formed into an apertured cage 12, provided with 90 valve seat 13 and a stem guide 14. Valve 15, usually of puppet type, coöperates with the valve seat and has a stem 16 about which is spring 17 acting between the cage 12 and suitable adjusting nuts 18 on the stem. The 95 fitting is also provided with a connection 19 for a pipe leading to the engine intake or mixing valve.

The regulator, constructed as described, is put in the usual position between a city 100 gas supply and the intake of a gas engine. The container is of a capacity adapted to the engine with which it is used, although containers of a given size will operate successfully with engines of different sizes. 105 Gas under ordinary pressure fills the container and bulges the side walls 2 somewhat and they because of their own flexibility and aided by the spring 3, exert a yielding pressure upon the gas in the container. The 110 check-valve 13 with its suitably proportioned spring 17 exerts a moderate retarding

effect upon the gas which goes to the engine through the connection 19 at each stroke. The cubic capacity of the container, its pressure upon the gas, and the retarding 5 and equalizing effect of the check-valve 13, acting together, have been found to very effectively eliminate fluctuations in the supply of gas to the engine and also fluctuations in pressure at the supply side of the 10 fixture, so that for example, a pilot light connected to the main at the intake side of the regulator is found to burn with great steadiness. It is also found that the appliance economizes gas, indicating that a 15 proper amount of gas is supplied to the engine at each stroke without the waste due to gas inertia effects and other disturbances caused by variations in pressure in the main. At the same time the appliance is very durable, being constructed entirely of metal. 20 The valve 13 and its seat are usually of phospher-bronze, upon which gas has no chemical effect. The container is practically proof against leakage, but if the side walls are 25 punctured by an accident they may be easily repaired by soldering. The appliance will in most cases last for years with practically no attention.

I claim,

- 30 1. In a regulator for the purpose described, a metallic container having thin, flexible metal side walls and supply and discharge connections for gas.
2. In a regulator for the purpose described, a metallic container having thin, flexible, substantially parallel metal sides and supply and discharge connections for gas.
3. In a regulator for the purpose described, a metallic container having thin, 40

flexible, substantially parallel metal sides, a spring connecting such flexible sides and supply and discharge connections for gas.

4. In a regulator for the purpose described, the combination of a metal container having flexible metal walls, a gas supply opening, a gas discharge opening and a spring-actuated check-valve intermediate the container and said discharge opening. 45

5. In a regulator for the purpose described, the combination of a metal container having a circumferential wall and thin, flexible metal side walls and a fitting secured to the circumferential wall, said fitting comprising a supply connection for 55 gas, a discharge connection, a check-valve opening in the direction of discharge and a spring urging the valve to seat.

6. In a regulator for the purpose described, the combination of a metal container having a circumferential wall and thin, flexible metal side walls, a contractile spring connecting the side walls and a fitting secured to the circumferential wall, said fitting comprising a supply connection 65 for gas, a discharge connection, a check-valve opening in the direction of discharge and a spring urging the valve to seat.

7. In a regulator for the purpose described, a container having side walls provided with small apertures, headed spring connections having stems passing through the apertures and a helical contractile spring connected to said stems, the apertures and spring being adapted to the insertion of the 75 spring by screwing it through one of the apertures, and supply and discharge connections for gas.

EDWARD A. REIN.
